UNITED STATES PATENT OFFICE.

HARLEY D. PENNINGTON, OF PITTSBURGH, PENNSYLVANIA, ASSIGNOR TO UNITED ENGINEERING AND FOUNDRY COMPANY, OF PITTSBURGH, PENNSYLVANIA, A CORPORATION OF PENNSYLVANIA.

PIPE-THREADING MECHANISM.

Application filed May 18, 1923. Serial No. 639,786.

To all whom it may concern:

Be it known that I, HARLEY D. PENNINGTON, a citizen of the United States, residing at Pittsburgh, in the county of Allegheny and State of Pennsylvania, have invented a new and useful Improvement in Pipe- Threading Mechanism, of which the following is a full, clear, and exact description.

The present invention relates to threading mechanism, and more particularly to pipe-threading mechanism.

In my copending application, Serial No. 624,759, filed March 18, 1923, there is shown and described a construction in which the threading die is automatically opened upon engagement of the end of the pipe being threaded with a reamer, the reamer actuating to released position a latch for holding the automatic die-opening means inoperative. Such construction is particularly adapted for threading pipe which comes to the threading machine in varying lengths and unreamed, since it embodies means for reaming and rounding the pipe, and cutting the same to length and trimming the ends thereof. However, it sometimes is desirable to use the cutting-off tool to cut off the ends of the pipe and face and ream the same; and furthermore, the pipe to be threaded often comes to the machine already cut to length and reamed so that the only operation to be performed thereon by the threading machine is the threading operation. The present invention provides gravity operated latch means for controlling the opening of the threading die and adapted to be directly engaged and actuated to released position by the pipe being threaded.

In the accompanying drawings, there is shown for purposes of illustration only, one embodiment of the present invention, it being understood that the drawings do not define the limits of the invention, as changes may be made in the construction and operation therein disclosed without departing from the spirit of the invention or scope of my broader claim.

In the drawings:

Figure 1 is a plan view of the reciprocating carriage of a pipe threading mechanism embodying my invention and the parts carried thereby,

Figure 2 is a view, partly in longitudinal

section and partly in elevation, of the parts illustrated in Figure 1,

Figure 3 is a front view of the threading die and the means constituting the embodiment of my invention which I have chosen to illustrate herein, and

Figure 4 is a view, partly in elevation and partly in section, of a portion of said means.

The threading die is made in two parts 14 and 15 mounted upon a die-head 16, each part being pivoted at its lower end upon a bolt 17 carried by said head. Each of the parts 14 and 15 is provided at its upper end with a pin 18 engaging in a cam slot 19 in a cam disc 20. It will be apparent that rotation of the cam disc 20 in one direction will cause the parts 14 and 15 to swing outwardly about the pivot bolt 17 to open the die, and that movement of said disc in the opposite direction will cause said parts to swing inwardly about said pivot bolt to close the die.

A connecting rod 21 is pivotally mounted at one end upon a pin 22 projecting upwardly from the cam disc 20, and at its opposite end is pivotally connected to one end of a lever 23. The lever 23, at its opposite end, is fixed to the upper end of a vertical shaft 24 journaled in the carriage C. A spring 25 is connected at one end to the lever 23, and at its opposite end to the carriage C, this spring tending to move the lever 23 in a direction to open the threading die. The cam disc 20 is provided with a handle 26, whereby said cam disc may be manually moved in a direction to close the threading die.

Fastened to the front of the die-head 16 is a bracket 32 provided with integral spaced arms 33. Extending between the bracket arms 33 and journaled therein by means of a pair of screw-bolts 34, is a boss 35 having an integral upwardly extending detent arm 36 for engagement with a shoulder 37 in the edge of cam disc 20.

Referring to Figure 4, it will be seen that the boss 35 is provided with a transverse opening 38, in which is slidably mounted the end portion 39 of a trip-arm 40. The screw-bolts 34, which constitute the journals for the boss 35, are screwed into the ends of the latter and engage the end portion 39 of arm 40 to thereby maintain said arm in any de-

sired adjusted position. In Figure 4 I have illustrated the arm 40 in one adjusted position in full lines and in another adjusted position in dotted lines.

- 5 The operation of the construction described is substantially as follows: The spring 25, through the lever 23 and link 21, normally maintains the cam disc 20 in such position as to hold the threading die open.
- 10 When the cam disc 20 is rotated into the position in which it is shown in Figure 1, the shoulder 37 is engaged by the end of the detent arm 36 to maintain the cam disc in such position. In this position of the cam disc the threading die is held closed. It will be apparent that the trip-arm 40 constitutes gravity-actuated means tending to rotate the detent arm 36 in a clockwise direction (Figure 4), whereby the end of said detent arm
- 15 is maintained always in engagement with the peripheral edge of the cam disc, so that said detent arm automatically engages the shoulder 37 as soon as the cam disc is rotated into the position in which it is shown in Figure 1. The operative may cause the rotation of the cam disc into this position either by means of the handle 26 or by moving the carriage C on the bed of the machine to engage the arm 31 of shaft 24, with a
- 20 stationary abutment, whereupon continued movement of the carriage in the same direction causes the arm 31 to be swung from the dotted line position to the full line position thereof shown in Figure 1, thereby effecting
- 25 the desired movement of the cam disc 20 to close the threading die. The pipe to be threaded is held in pipe-rotating means which holds the pipe against axial movement, so that the threading operation causes
- 30 the carriage C to move towards the pipe-rotating means until the end of the pipe engages the trip-arm 40, whereupon continued movement of the carriage C towards the pipe rotating means causes said trip-
- 35 arm to be raised, thereby rocking the detent arm 36 out of engagement with the shoulder 37 of the cam disc 20. Immediately that this occurs, the spring 25, through the lever 23 and link 21, effects rotation of the cam disc

in the direction of the arrow (Figure 1), 50 thereby opening the threading die. The edge portion 20' of the cam disc 20 adjacent the shoulder 37 is eccentric with respect to the axis of rotation of said disc, so that the rotation of the disc in the die-opening direction insures the raising of the trip-arm 40 to a sufficient height to clear the incoming pipe.

It will be apparent that the length of the thread cut upon the end of the pipe may be 60 predetermined in accordance with the adjustment of the trip-arm 40 in the boss 35. It will also be apparent that the provision of the latch means described for controlling the operation of the automatic die-opening 65 means renders the operation of said die-opening means entirely independent of any other operation on the pipe, such as the reaming operation.

The advantages of the present invention 70 arise from the provision of latch means of simple construction which may be readily applied to existing types of pipe-threading mechanisms for controlling the operation of automatic die-opening means, and which 75 latch means operates entirely independently of any operation except the threading operation.

I claim:

In a pipe threading machine, a die head, 80 threading dies pivotally mounted thereon, a cam for opening and closing said dies, spaced arms projecting forwardly from said head, journal members adjustably mounted in said arms, an upwardly extending detent 85 arm journaled between said spaced arms on said journal members and adapted to engage a shoulder on the periphery of said cam, and a trip arm slidably mounted in said detent arm and held in adjusted position by said 90 journal members, said trip arm being arranged to be engaged by the end of the pipe being threaded whereby to move said detent arm to released position.

In testimony whereof I have hereunto set 95 my hand.

HARLEY D. PENNINGTON.
